UNITED STATES PATENT OFFICE.

MARCEL J. RENAUD, OF MONROE, LOUISIANA.

WALL STRUCTURE.

Application filed January 25, 1928. Serial No. 249,393.

This invention relates to an improved wall structure and method of forming and applying the same.

Heretofore, it has been the practice to apply to wall studding, first the ship-lap or siding, second, some water proofing material such as tar paper, third, the metal lathing, and finally the stucco or plaster is applied. These are all separate operations, and take considerable time and of course each operation adds materially to the cost of the structure. It is the primary purpose of my invention to eliminate the necessity of applying the siding and water proofing paper, at the time of erection of the structure, by providing a stucco receiving base consisting of metal lathing with wall board permanently attached thereto, so that when the structure is to be erected, it is merely necessary for the operator to secure the already assembled wall board and lathing to the studding, and the only other operation necessary is the stuccoing or plastering, which may be done in a uniform and efficient relation, without any considerable skill.

Among the very important objects of this invention is the provision of a wall structure and a method of forming and applying the same which will do away with the conventional operations of applying siding and tar paper; which is economical and saving in labor; by means of which an even plastered wall surface may be absolutely attained; by which a wall of uniform strength and thickness is secured, and by means of which a solid reinforced sheet wall of cementitious material is provided, without voids.

Other objects and advantages of this invention will be apparent during the course of the following detailed description.

In the accompanying drawing, forming a part of this specification, and wherein similar reference characters designate corresponding parts throughout the several views,

Figure 1 is a fragmentary perspective view of the assembled expanded metal and wall board, showing novel features.

Figure 2 is a fragmentary vertical sectional view taken through a wall structure, showing the application of the improved lathing and wall board to studding, and with the stucco or plaster received thereon.

Figure 3 is a fragmentary vertical sec-

tional view taken through the novel assemblage of wall board and metal lathing.

In the drawings, wherein for the purpose of illustration is shown only a preferred embodiment of the invention, the letter A may generally designate my improved stucco receiving structure, which may consist of expanded metal lathing B having wall board C secured thereto in a novel relation.

The lathing or sheathing B is preferably of the expanded metal type, including the body mesh 10, expanded in the usual manner to provide openings 11 therebetween through which plaster and stucco may readily pass. Preferably parallel ribs 12 are provided upon the lathing B, to stiffen and reinforce the same; these ribs preferably being of V-shaped formation, and extending beyond the plane of the mesh 10 for any desired distance, according to the type of structure in which the wall is being formed. In the example shown, the ribs 12 are of V-shaped formation, with leg or flange portions 13 and 14, extending from the plane of the mesh 10 to the apex or outer edge 15, and which edge 15 is normally adapted to abut against the stuccoing or siding in conventional wall formation, as will be well understood by those skilled in the art to which this invention relates. As a departure from conventional practice I prefer to stamp or otherwise form upon the rib 12 substantially triangular securing projections 18, extending from the edge 15 of each of the ribs 12, and projecting outwardly therefrom in a pointed relation. The projections 18 are preferably stamped from one of the legs or flanges 13 and 14, or from both, so that when bent outwardly normal to the ridge line of the rib 12, a triangular opening 20 will be provided in the rib 12, and the base of the triangular projection 18 is of course at the ridge line of the rib 12, and extends with its apex or point 23 in a direction normal to the plane of the expanded metal lathing. These projections 18 are preferably one-half inch or so in height, and are provided for the purpose of holding and securing the wall board C thereto in a relation illustrated in Figure 1. The wall board C may be of composition paper, plaster, gypsum, or the like, although it is preferably water-proof. The wall board C is either rigid or semi-rigid, with an inherent tendency to maintain its form, and it is of a thickness which will permit the same

to be forced upon the metal lathing at the rib side of said lathing, so that the projections 18 of the lathing are driven through the material of the wall board to project 5 from the outer side of the wall board. These projecting from the outer side of the wall board are then turned over, as shown at 40 in Figure 1 of the drawings, and the wall board lies flat upon the ridge edges of 10 the ribs 12, in spaced channel or pocket providing relation with the mesh body 10 of the lathing, and in which channels or pockets the stuccoing or plastering is adapted to be filled.

15 It is preferred that the wall board C and lathing B be assembled in this relation at the factory, and shipped to contractors and the like for erection in this assembled relation into the building structure. It is of 20 course foreseeable that the expanded metal with the triangular projections 18 may be assembled with the wall board C at the building site, but for economical and labor saving reasons the wall board and lathing 25 are already assembled when the contractor or architect receives the same.

Referring to the assemblage of the structure A in providing a wall or the like, the lathing with its water proofed backing or 30 wall board assembled thereto are attached directly to the studding in the same manner as lathing heretofore has been fastened to studding or siding, that is, by driving nails or staples 51 through or in an embracing 35 relation with the ribs 12; the wall board C being faced against the studding 52, as shown in Figure 2. As thus secured in place the backing or wall board C is against the studding 52, with the mesh body 10 of the 40 metal sheathing or lathing B in uniformly spaced relation with the wall board C. It is thus obvious that the conventional operations of applying siding and tar paper or other water proof paper are done away with 45 during the building operation. The plaster or stucco is then applied, and the operator may easily force the stucco into and through the mesh 10 between the same and the wall board C, to fill the pockets and channels 50 therein without the formation of voids. The plaster or stucco is then applied to the uniform depth desired over the outside of the metal lathing or sheathing. The wall structure A may be applied to exterior or interior walls. It is known that in ordinary 55 plastering operations using steel lathing, the plasterers bend the lathing in uneven thicknesses, which gives an eccentric and non-

uniform strength. However, with my wall board attached to the ribs of the lathing, 60 in advance of the application of the structure A to the studding, the spacing is such that the mortar will press evenly into the pockets between the lathing mesh and wall board and completely fill the spaces. This 65 produces a sheet of reinforced cementitious material which gives a uniform and therefore increased strength to the entire wall structure. The uniformity in the thicknesses of the pockets in this structure, enables the contractor to determine accurately 70 the amount of materials which any job will require, and thus costs may be determined without speculation.

It is obvious from the foregoing that a 75 novel structure and method of forming and applying the same has been produced, which is superior to conventional methods of application and formation.

Various changes in the steps of the 80 method, and in the shape, size, and arrangement of parts may be made to the form of invention shown and described, without departing from the spirit of the invention or 85 the scope of the claims.

I claim:

1. Building material consisting of reinforced metal lathing including a mesh body and metal ribs with pointed projections rigid therewith, and substantially impervious wall 90 board secured by the pointed projections on the ridge edges of the ribs in spaced relation with the mesh body.

2. A wall structure of the class described 95 expanded metal lathing provided with integral rigid pointed projections, and wall board secured to said projections in spaced relation with the body of said metal lathing.

3. Ready to apply combination wall board 100 and metal lathing comprising expanded metal lathing having a mesh body and ribs outstanding therefrom, and wall board secured to said ribs in spaced relation with the mesh body.

4. Ready to apply combination wall board 105 and metal lathing comprising expanded metal lathing having a mesh body and ribs outstanding therefrom, and wall board secured to said ribs in spaced relation with the mesh body, said wall board being secured 110 to the ribs by pointed projections rigid with the ribs and extending through the wall board and overturned on the wall board at the opposite side from said ribs.

MARCEL J. RENAUD.
